CONTROL FOR THE UNREELING OF COILED MATERIAL FROM DRUMS

Howard C. Porter, Chicago, Ill., assignor to Sig-node Steel Strapping Company, Chicago, Ill., a corporation of Delaware

Original application August 4, 1936, Serial No. 94,199. Divided and this application November 15, 1937, Serial No. 174,527

6 Claims. (Cl. 206—53)

My invention relates to controls for the unreeling of coiled material from drums.

It is particularly suitable for and will be explained in connection with the unreeling of metallic package-binder strap from a revoluble coil-supporting drum.

One of the objects of my invention is to provide an improved control-spring for preventing looseness and overfeed of coils of material, such as package-binder strap.

Another object is to provide a control-spring that is effective and easily applied.

Another object is to provide a control-spring which permits easy re-coiling in the event more material than needed has been withdrawn from the coil.

Other objects and advantages will hereinafter appear.

An embodiment of the invention, particularly adapted for metallic flat package-binder, is illustrated in the accompanying drawings wherein:

Fig. 1 is a perspective view of my control spring applied to the revoluble drum of the portable strap-reel;

Fig. 2 is an enlarged vertical section through the drum of the reel, showing the normal location of the control-spring;

Fig. 3 is a top view of the drum with the control-spring in place;

Fig. 4 is a perspective of the two control-spring sections, showing them disconnected or unjoined and slightly separated, but otherwise rather clearly showing their relative position when in use;

Fig. 5 is an enlarged top plan, partly in section, of the detachable connection between the spring-sections, which connection serves as a guide through which the strap is fed from the coil, and

Fig. 6 is an enlarged side elevation of the section-connector and guide.

This application is a division of my copending application Serial No. 94,199 filed August 4, 1936.

In general, my control comprises a two-sectioned spring for frictionally and resiliently surrounding and bearing upon the curved periphery of the coil of material, the complementary sections being detachably joined by a separable connector through which the material is fed intermediate the ends of the composite spring.

In Fig. 1 I have shown the control spring applied to a coil of metallic strap—such as used for package binding—carried upon the rotatably supported drum of a portable reel. The drum includes a generally cylindrical barrel 10 upon

which the strap coil is supported and a pair of coil-retaining heads 11.

The spring comprises in general two complementary and separable sections 15 and 16 made from spring steel—preferably flat—bent into helical or generally circular form and of a length normally almost to form a complete circle having a diameter slightly less than that of the barrel of the drum with which it is to be used. If the spring is to be used with a drum having coil-retaining heads, the width of its sections should be slightly less than the distance between the drum heads.

The proximate ends of spring sections 15 and 16 are equipped with cooperating coupling members 17 and 18, respectively, whereby the two spring sections may be readily coupled together end to end with a relatively small gap therebetween and, when occasion requires, easily separated. Coupling member 17 comprises a stirrup 19, one end of which is rigidly attached to the end of spring section 15 in a suitable manner, such as by welding. The other end of stirrup 19 is bent outwardly at 20 and then rearwardly or reversely at 21 to accommodate the flange or hook 22 of a substantially U-shaped latch bolt 23.

A spacer strip 24, somewhat shorter than the length of the flange-hook, is located between hook 22 and the stirrup 19 so that when these two members are secured together by rivets 25 or other appropriate means, there is provided a laterally opening rectangular slot or bolt-socket 26. Coupling member 18 likewise comprises a stirrup 27 having one end attached to the end of spring section 16 and the other end bent outwardly and rearwardly to accommodate a hook-shaped flange 28 of a latch bolt 29, which flange is riveted to stirrup 27 with a spacer strip 30 therebetween to form a rectangular slot or bolt-socket 31 which opens laterally in the opposite direction from the socket 26.

With this arrangement the two control spring sections may, by relative lateral movement, be separated, as shown in Fig. 4, more readily to enable the ring to be removed from and applied to the drum; but they may be coupled together by interlocking the coupling members sidewise, the end 32 of latch bolt 23 entering the bolt-socket 31 and the end 33 of latch bolt 29 entering bolt-socket 26. When the two coupling members are thus joined, the spring sections are coupled together end to end to form a ring, but the proximate ends are separated by a gap or guideway 34 through which the free end 35

of a coil 36 of coiled material (e. g., coiled package-binder strap) may be threaded, as shown most clearly in Figs. 2 and 6. With the two coupling members united and the control ring 5 in position about the coil of strap, the coupling members lie below the rims of the drum heads and are prevented from accidental separation thereby. Furthermore, the cooperative action of the rectangular-hook-shaped latch bolts 23 10 and 29 fitting the rectangular sockets 31 and 26, causes the guideway to form a rigid end to end coupling between the control ring sections, giving the control ring the effect of a single spring substantially surrounding and resiliently 15 and frictionally bearing upon the external curved surface of the coil of strap.

Thus, the strap is fed from the coil in the drum through a gap or guide in the midregion of the control spring, the two sections of which 20 overlap and completely encircle and bear resiliently inwardly—as well as frictionally—against the outer surface of the coil.

The formation of the control spring in two substantially equal-length readily separable sections 25 permits the use of a long control spring—one which may completely surround the coil of material—and facilitates the proper positioning thereof upon and the easy removal thereof from the strap coil. The feeding of the strap from the coil through a guide at the midregion of 30 the control spring-ring, overcomes the tendency—when the strap is pulled to withdraw it from the coil—to raise the control spring out from between the heads of the drum—an objectionable tendency when the strap is fed out 35 from under one end of an encircling control spring. And the easily manipulated latch coupling between the two sections which permits the sections to be readily separated and reunited 40 facilitates the placement of the control spring between the drum heads and about a coil of strap supported upon the barrel thereof. The effect of gradual curves provided by the outwardly sloping portions of the stirrups 19 and 27 permits the somewhat stiff strap to leave the 45 coil and be led out through the control ring guideway without sharp bends therein.

As strap is needed it is drawn from the drum by a pull on its free end—the drum and coil 50 rotating to allow the strap to unwind. The friction of the control spring urges it to rotate with the coil and drum, but it cannot pass the strap threaded through its central guideway; it is forced to remain relatively stationary as long 55 as the unwound portion of strap is held taut by the operator. Thus, the coil and drum rotate inside of and relative to the control spring with a friction which, although usually relatively light, may be varied by changing the overlap of the sections of the control spring.

60 For the lighter braking effects the control spring sections are assembled as shown in Fig. 2, with the inner or free end 40 of section 16 inside of the other section (i. e., directly against the peripheral surface of the coil) so that the pull on the strap end and the rotation of the coil (as shown by the arrow) is against the inner tip of one of the control spring sections (i. e., the tip 40 of coil spring section 16). This 65 action causes that section to tend to unwind or loosen its grip upon the surface of the coil,—thereby tending to decrease the friction and the resilient pressure upon the coil.

70 For the heavier braking effect the control spring sections are assembled reversely (e. g.,

with the inner or free end 41 of section 15 bearing directly against the peripheral surface of the coil) so that the friction of the rotation tends to wind the inner of the two spring sections more tightly about and upon the surface of the 5 coil. Such action tends to increase the frictional and resilient pressure upon the coil. This braking effect provides two variations of what ordinarily should be a relatively light back-tension. This is a desirable factor to assist in insuring 10 that material (e. g., metallic binder straps) of different characteristics can be drawn reasonably straight and taut from a supply coil thereof.

As soon as movement of the free end of the strap ceases, the momentum of the coil and drum is effectively braked by that same action. The strap is held clamped tightly and flatwise into the coil under the action of the control spring at all times; no loose or slack laps or convolutions being free to pull away from the coil or 20 to get out of the channel between the flanges of the reel-drum or, if the material is flat strap, to turn up on edge and cause tangles.

The tendency of a relatively heavy coil and drum to rotate and overrun and thereby continue to deliver strap after the operator has ceased to pull is also reduced by the grip of the control spring preventing any substantial increase in the diameter of any lap or convolution in the coil and resulting looseness from 30 such overrunning. This action of the spring forces the momentum to be rapidly overcome by the friction of loosening and slipping many laps or convolutions of strap, each of small amount, because the only possible escape for additional 35 length of material by overrun is that slight increase in diameter allowed by the inward pressure of the spring.

On long pulls, when considerable lengths of strap are taken very rapidly from a drum, it is often desirable, when the required footage has 40 been drawn off, to slack back on the free end which removes the impedance of the taut strap against rotation of the control spring with the drum. The spring then clamps and rotates with the coil and drum, winding the slack reversely 45 outside of the control spring until a slight pull on the free end has stopped the overrun (usually in less than one revolution of the drum), whence that small amount of wound-back strap can be drawn quickly and freely at slow speed. 50

In the event more strap than required is drawn from the drum, the control ring and its guideway form an easy means for insuring a quick and proper rewind upon the coil of the excess. Thus, by holding the control ring stationary and 55 rotating the drum in the reverse direction, the excess strap can be tightly, evenly, and flatly rewound upon the coil.

The bent back portions 21 of the section-coupling members being spaced some distance 60 outside of the curve of the spring serve as convenient handles for lifting the coupling above the rims of the drum flanges so that it may be disconnected for easy spring removal. As handles they also facilitate the interlocking of the 65 coupling-sections when a spring is being positioned about a coil and they provide a convenient grip for holding the control ring in the event strap is to be rewound upon the coil.

Having thus illustrated and described the preferred embodiment of my invention, what I claim and desire to secure by United States Letters Patent is as follows:

1. A spring for controlling the unreeling of coiled material comprising a pair of spring sec- 75

- tions, each consisting of a length of spring steel curved to fit about and press upon the external surface of the coiled material; and a coupling member secured to an end of each spring section 5
- 5 each coupling member having a hook spaced outwardly from the end of its associated spring section and a socket, the socket of one coupling member detachably receiving the hook of the other coupling member, said coupling members
- 10 when united joining the two spring sections into a unitary spring ring and providing a guideway between the spaced proximate ends of the spring sections through which material may be fed from the coil.
- 15 2. A spring for controlling the unreeling of coiled material comprising a pair of spring sections, each consisting of a curved piece of spring steel of a length such that when the two pieces are placed end to end with a gap therebetween 10
- 20 they at least partly encircle and bear upon the external surface of the coiled material; and a separable connector for rigidly joining the two spring sections end to end with a gap therebetween whereby the composite spring friction- 15
- 25 ally and resiliently bears upon the external surface of the coiled material and the free end of the material may be fed from the coil through the gap between the sections.
3. A spring for controlling the unreeling of 30
- 30 coiled material comprising two sections of flat spring steel bent into a partial circle and having a length such that when the two sections are placed end to end with a gap therebetween they overlap each other and encircle and press 35
- 35 upon the external surface of the coiled material; and a pair of coupling members, each attached to an end of one of the spring sections and each having a bolt portion spaced from the adjacent end of its associated spring section, and 40 a bolt-socket, the bolt of one coupling member
- detachably fitting into the bolt-socket of the other coupling member detachably to join the spring sections together end to end with a gap therebetween, the spring sections when joined serving as a ring which frictionally and resiliently bears upon the coiled material and through the gap of which the free end of the material may be fed from the coil. 5
4. A spring for controlling the unreeling of coiled material comprising a pair of spring sections arranged end to end and curved into generally circular shape to fit about and bear upon the periphery of the coiled material, and a separable connector for joining together the proximate ends of the two sections, there being an 15 opening through the composite spring intermediate its remote ends for the feeding there-through of the ends of the coiled material.
5. A spring for controlling the unreeling of coiled material comprising a pair of wholly separate spring sections, each consisting of a length of spring steel sufficient to overlap the other in use and curved to fit about and bear upon the curved periphery of the coil of material; and a separable connector for detachably joining the 20 25 spring sections at one end in spaced relation and permitting the coiled material to be led from the coil through the gap between the spring sections.
6. A spring for controlling the unreeling of 30
- 30 coiled material comprising a pair of wholly separate elastic sections arranged end to end and partly in overlapping relation, and curved into generally circular shape to fit about and press upon the curved periphery of the coiled material, and a coupling for connecting together the proximate ends of the elastic sections with a gap therebetween through which the end of the coiled material may be fed. 35

HOWARD C. PORTER. 40
